US00D566055S

(12) **United States Design Patent** (10) **Patent No.:** **US D566,055 S**
Kim (45) **Date of Patent:** **** Apr. 8, 2008**

(54) **LIGHT-EMITTING DIODE (LED)**

(75) Inventor: **Wan Ho Kim**, Gwangju (KR)

(73) Assignee: **LG Innotek Co., Ltd.**, Seoul (KR)

(**) Term: **14 Years**

(21) Appl. No.: **29/274,017**

(22) Filed: **Mar. 21, 2007**

(30) **Foreign Application Priority Data**

Sep. 21, 2006 (KR) 30-2006-0038840

(51) **LOC (8) Cl.** 13-03

(52) **U.S. Cl.** **D13/180**

(58) **Field of Classification Search** D13/180;
D26/2; 257/79, 80, 81, 88, 89, 95, 98, 99,
257/100; 313/483, 498, 500; 362/555, 800

See application file for complete search history.

(57) **CLAIM**

The ornamental design for a light-emitting diode (LED), as shown and described.

DESCRIPTION

FIG. 1 is a front, right perspective view of the light-emitting diode (LED) showing my new design;

FIG. 2 is a front view thereof, the rear view being a mirror image thereof;

FIG. 3 is a left side view thereof, the right side view being a mirror image thereof;

FIG. 4 is a top plan view thereof; and,

FIG. 5 is a bottom plan view thereof.

1 Claim, 2 Drawing Sheets
